United States Patent Office.

JAMES A. HERRON, OF TALLEY CAVEY, PENNSYLVANIA.

Design No. 4,884, dated May 9, 1871.

DESIGN FOR A HAY-RACK.

The Schedule referred to in these Letters Patent and making part of the same.

To all whom it may concern:

Be it known that I, JAMES A. HERRON, of Talley Cavey, in the county of Allegheny and State of Pennsylvania, have invented and produced a new and original Design for Hay and Grain-Rack; and I do hereby declare that the following is a full and exact description thereof, reference being had to the accompanying drawing and to the letters of reference marked thereon.

The nature of my design is fully represented in the accompanying drawing, to which reference is made, and which forms part of my specification.

Figure 1 is a perspective view of my improvement in design for hay and grain-rack.

Figure 2 is a side elevation of the same, representing a portion of the tongue broken away.

A represents two very low supports, made in the form of "sled-runners," into which are fitted cross-pieces B, on which are secured, at x, a series of thin and narrow strips, C.

The rack is provided with pins, represented at e and f.

The rack is provided with a draft device, represented at D, and a tongue, represented at h, and pivoted on the pin e.

As the form and configuration of my improvement in design for hay and grain-rack will readily be understood from the foregoing description, and by reference to the accompanying drawing, I will, therefore, proceed to describe the object and advantages of my improvement in design for hay and grain-rack.

The supports A are made low and in the form represented for a twofold purpose—first, for the purpose of drawing the rack from place to place in the field, and from the field to the barn or other place; and, in the second place, they are made low for the purpose of readily and easily lifting the hay when gathered in "windrows" or "cocks," or the grain when in sheaves and shocks onto the rack.

The strips C are made thin and narrow for the purpose of lightness, and are secured on the cross-pieces B for the purpose of giving them the form, when viewed edgewise, shown in fig. 2, and are secured as indicated at x for obtaining strength.

By hitching a horse or a pair of horses to the rack at D, as indicated by the dotted lines y, it can be drawn to any part of the field, and from the field to the barn or place where the hay or grain is stored or stacked.

The tongue h is used for the purpose of preventing the rack from running against the heels of the horse or horses when drawing the rack down on land which is sloping or inclined.

The pins e and f are used for holding the hay or grain in position on the rack.

The hereinbefore-described hay or grain-rack may be placed on the ordinary sled, and used for the purpose of transporting and conveying hay or grain from one place to another.

The advantage of the shape and configuration of the rack hereinbefore described has been demonstrated to be very great to the farmer in gathering in hay and grain.

My design for hay and grain-rack is not intended for the ordinary sled, and I do not claim it as a design for sleds.

Having thus described the nature, object, and advantages of my design for hay and grain-rack,

What I claim as of my invention is—

The shape and configuration for a hay or grain-rack herein described, and shown in the accompanying drawing.

JAMES A. HERRON.
